UNITED STATES PATENT OFFICE.

S. ROBERT SCHWARTZ, OF NEW YORK, N. Y.

DESIGN FOR A PORTABLE LAMP-BASE.

59,132.

Specification for Design.

Patented Sept. 20, 1921.

Application filed October 20, 1920. Serial No. 418,340. Term of patent 7 years.

To all whom it may concern:

Be it known that I, S. ROBERT SCHWARTZ, a citizen of the United States of America, residing at New York, in the county of New York and State of New York, have invented a new, original, and ornamental Design for Portable Lamp-Bases, of which the following is a specification, reference being had to the accompanying drawings, forming part thereof.

In the drawings

Figure 1 is a perspective view of my new lamp base according to my design,

Fig. 2 is a plan view of the same, and

Fig. 3 is a view illustrating the use of my lamp base.

I claim:

The ornamental design for a portable lamp base, as shown.

In testimony whereof, I have signed my name to this specification in the presence of two subscribing witnesses, this eighteenth day of October, 1920.

S. ROBERT SCHWARTZ.

Witnesses:

I. SMITH,

A. BOSTROEM.
